UNITED STATES PATENT OFFICE

2,350,714

ORNAMENT

Eugene Bazner, Providence, R. I.

Application January 6, 1943, Serial No. 471,391

8 Claims. (Cl. 63—2)

My invention relates to improvements in jewelry ornaments particularly of the type having a portion actually simulating a gem or a cluster of gems, as often referred to in the trade as "pavé" or gem paved.

As stated and shown in my joint Patent No. 2,246,399 for Jewelry ornament, when making such gem simulating surfaces in the prior art, said gems have only been simulated by providing indentations in the ornamented surface. An indentation is the complement of what is actually seen in a gem and an indentation therefore never gives the perspective effect provided by a gem. I may simulate a gem by providing a gem simulating mound comprising a multi-faceted frusto-pyramidal mound with the facets of the mound inclined similarly to those of the gem to be simulated. While these may be manufactured by the casting method shown in said patent and as shown herein, it is obvious that such a type of ornament is new no matter how made.

A further feature of my invention is that I provide a gem simulating portion comprising a center portion consisting of a plurality of similarly inclined facets arranged in pyramidal, preferably frusto-pyramidal, formation. Said formation comprises a cavity or a mound and a border portion consisting of a plurality of similarly inclined facets arranged in reverse frusto pyramidal formation around said center portion with the facets of the center and border portions being similar to the gem being simulated, whereby the upwardly and downwardly tilted facets may visually cooperate with each other to simulate a gem. So far as I am aware, I am the first to provide a gem simulating ornament covering this combination of reversely inclined center and border facets and it is apparent that this combination much more accurately simulates a gem than a mere indentation as shown in my joint Patent No. 2,246,399.

A further feature of my invention resides in the fact that the arrangement of center portion and border portion actually simulates the facets on an actual stone for perspective effect, a feature not possible in prior art structures.

A further feature of my invention is to provide a plurality of such portions, each plurality being closely nested together as to provide a pavé or a gem paved surface regardless of how it may be made.

Further features of my invention relate to improvements in the apparatus for and method of making my improved ornament.

These and such other objects of my invention

as may hereinafter appear will be best understood from a description of the accompanying drawings which illustrate embodiments thereof.

In the drawings,

5 Fig. 1 is a plan view of a jewelry ornament constructed in accordance with my invention in which the facets of the border portion project outwardly to form mounds and the facets of the center portion incline inwardly to provide cooperating indentations.

Fig. 2 is a sectional view taken along the line 2—2 of Fig. 1.

Fig. 3 is a perspective view of a single gem simulating mound.

15 Fig. 4 is a sectional view similar to Fig. 2 of an ornament constructed in accordance with my invention wherein the facets of the border portion are inclined inwardly and the facets of the center portion are inclined outwardly.

20 Fig. 5 is a perspective view of a single gem forming portion constructed as shown in Fig. 4.

Fig. 6 is a perspective view of an alternative type of ornament constructed in accordance with my invention.

25 Fig. 7 is a perspective view of the back mold plate, and

Fig. 8 is a perspective view of the front mold plate making up a suitable mold for the manufacture of my invention.

30 Fig. 9 is a sectional view taken through the front plate of my improved mold along the line 9—9 of Fig. 8 with a single facet forming pin removed.

35 Fig. 10 is a cross-sectional view of the front and back plates of the mold and also showing the ornament in section after the ornament has been formed by the cooling of the metal poured in between the mold plates in the manner shown in said patent and showing the back die plate being removed from the front die plate containing the cast ornament.

40 Fig. 11 is a cross-sectional view of a front die plate capable of producing the article shown in Fig. 4.

45 In the drawings, wherein like characters of reference generally indicate like parts throughout, 20 and 20' generally indicate an ornament constructed in accordance with my invention. Although as stated I obtain good results by casting

50 my improved ornament, it is believed the subject matter thereof is novel no matter how made whether by casting, stamping, burnishing or otherwise. Said ornament is provided with a gem simulating ornament surface 22. While said surface may comprise that of a single gem as shown

at 22a in Fig. 6, it preferably comprises a gem paved surface extending throughout a substantial predetermined area of the ornament surface as the surfaces 22 shown in Figs. 1 and 6. Said surface 22 whether comprised of a single gem or a plurality of gems has either a single gem simulating portion 24 or a plurality of gem simulating portions 24 making up a gem paved ornament surface 22. Each gem simulating portion comprises a center portion 26 and a border portion 28. The border portion 28 consists of a plurality of similarly inclined facets 32 arranged in frusto-pyramidal formation. In the embodiment shown in Figs. 1 to 3 the facets project upwardly in true frusto pyramidal formation providing a mound. In the embodiment shown in Figs. 4 and 5, the facets 32' of the border portion 28' incline inwardly to form the reverse frusto pyramidal formation or indentation 26'. As stated hitherto, so far as I am aware it is new to provide the pyramidal mounds 26 hitherto described.

As also stated, a main feature of my invention consists of providing a center portion 26 comprising a plurality of similarly inclined facets 30 arranged in reverse frusto-pyramidal formation to that of the facets 32 of the border portion. Thus, in the embodiment shown in Figs. 1 to 3, said facets 30 form a cavity or concave crater having preferably a flat center portion 34 and in the embodiment shown in Figs. 4 and 5, said facets 30' form a mound 26' preferably having a flat center portion 34'. Said center portions therefore comprise the preferably flat center portions 34 and 34' and the facets 30 and 30' arranged around the center portion in frusto-pyramidal formation whether the facets incline downwardly to form indentations 26 as shown in Figs. 1-3 or upwardly to form center mounds 26' as shown in Figs. 4 and 5. It is thus obvious that in either embodiment the facets 30 or 30' of the center portion 26 or 28' incline in reverse frusto pyramidal formation to those 32 or 32' of the border portion 26 or 28'. The gem simulating portions 24 or 24', where a pavé surface 22 is desired, are preferably so closely nested as to have the outer walls of each border portion substantially abut the outer walls of adjacent border portions to provide a true pavé effect. Best results are obtained where both facets 30 and 32 and 30' and 32', if two sets of facets are employed to make up center and border portions 26 and 28 respectively, are similar to those of the gem to be simulated and are provided with highly reflective brilliant surfaces. It is thus obvious that this double set of facets 30 and 32 or 30' and 32' more closely simulate the gem than any prior gem simulating portion in a gem simulating ornament.

The gem simulating portions 24 or 24' may be arranged in stripes, scrolls, circles, leaves or any other well known design known in the art.

It is apparent that the pavé surface 22 may be formed in regular hexagonal relationship all over the pin surface 22 as shown in Figs. 1-3 or it may comprise the irregular pavé surface of a leaf as shown in Fig. 6.

As also stated, the idea of providing mounds in gem simulating portions of this description is broadly new no matter how made and the combination of oppositely inclined facets making up the center and border portions is also broadly new however made.

I have found, however, a convenient method of manufacturing such ornaments is by casting as shown in my joint Patent No. 2,246,399 in which

the highly reflective brilliant border facet forming surfaces 36 and center facet forming surfaces 38 may be readily transferred from the highly burnished facets 40 forming the border portion 42 of a die, said facets in said border portion being formed as mounds 42' in the embodiment shown in Fig. 11 or as cavities 42 in the embodiment shown in Fig. 10 right in the die itself. The facets 30 of the center portion 26 may as shown in said application be transferred from the highly burnished facets 44 on the ends 46 of suitable pins 48 projecting through suitable holes 50 in spaced relationship within a die 52 shaped as hereto described to form the outer border facets 32 or 32', as shown in Figs. 9 and 10 and thus the ends 46 of the pins 48 project upwardly in frusto pyramidal formation. As shown in Fig. 11 the center facets project downwardly to form an indentation 46' in the upper end of each respective pin 48.

A suitable respective front plate 52 is shown in Fig. 8 and a suitable respective back plate 54 is shown in Fig. 7. Said plates are provided with hemi-funnel indentations 56 extending from the upper ends 58 thereof and arranged in suitable relationship to guide molten metal into the mold cavity 60 formed in the front die plate. Thus when the front and the back plates are arranged in juxtaposition, a conduit will be provided leading to the mold cavity 60. The front die plate 52 is provided with suitable aligning projections 62 adapted to project into suitable aligned cavities 64 in the back die plate to keep the plates in alignment as the metal is cooled in the mold cavity 60. It is apparent that an ornament 20 or 20' is cast within said cavity and may be suitably removed from said cavity after the relative movement of the back plate 54 away from the front plate 52 as illustrated in Fig. 10. If desired, the outer wall of each pin 48 is preferably corrugated as shown at 66 to provide a plurality of spaced grooves for the withdrawal of air from the cavity as the molten metal is being inserted as shown in said patent. It is apparent that the facets 40 or 40' and 44 or 44' of the cavity form cooperating facets 32 or 32' and 30 or 30' of the border and center portions respectively of each gem simulating portion 24 or 24'.

As also stated, the ornament may be made of any desired shape and the gem simulating portions may be made to simulate any shaped gem and arranged in any desired shape or relationship. Facets may be so formed as to simulate different cuts or forms of gems. Where the ornament is made by casting, any suitable type of low melting point metal or plastic may be employed. A typical metal may therefore comprise 90 per cent tin and remainder of antimony, cadmium and/or lead in suitable proportions.

It is understood that my invention is not limited to the specific embodiments shown and that various deviations may be made therefrom without departing from the spirit and scope of the appended claims.

What I claim is:

1. An ornament having a gem paved simulating ornamental surface comprising a plurality of gem simulating portions integral with said ornament each comprising a center portion consisting of a plurality of similarly inclined facets arranged in frusto-pyramidal formation and a border portion consisting of a plurality of similarly inclined facets arranged in reverse frusto-pyramidal formation around said center portion, so closely nested as to have the faceted

outer walls of each border portion substantially abut the faceted outer walls of adjacent border portions, with the facets of the center and border portions being similar to those of the gems to be simulated and having highly reflective brilliant surfaces whereby the upwardly tilted and downwardly tilted facets may visually cooperate with each other to simulate gems.

2. An ornament having a gem paved simulating ornamental surface comprising a plurality of gem simulating portions integral with said ornament, each comprising a center portion consisting of a plurality of similarly inclined facets arranged in pyramidal formation and a border portion consisting of a plurality of similarly inclined facets arranged in reverse frusto-pyramidal formation around said center portion, so closely nested as to have the faceted outer walls of each border portion substantially abut the faceted outer walls of adjacent border portions, with the facets of the center and border portions being similar to those of the gems to be simulated and having highly reflective brilliant surfaces whereby the upwardly tilted and downwardly tilted facets may visually cooperate with each other to simulate gems.

3. An ornament having a gem paved simulating ornamental surface comprising a plurality of gem simulating portions integral with said ornament, each comprising a center portion consisting of a plurality of similarly inclined facets arranged in pyramidal formation and a border portion consisting of a plurality of similarly inclined facets arranged in reverse frusto-pyramidal formation around said center portion, with the facets of the center and border portions being similar to those of the gems to be simulated and having highly reflective brilliant surfaces whereby the upwardly tilted and downwardly tilted facets may visually cooperate with each other to simulate a gem.

4. An ornament having a gem simulating portion integral with said ornament comprising a center portion consisting of a plurality of similarly inclined facets arranged in pyramidal formation and a border portion consisting of a plurality of similarly inclined facets arranged in reverse frusto-pyramidal formation around said center portion, with the facets of the center and border portions being similar to those of the gem to be simulated and having highly reflective brilliant surfaces whereby the upwardly tilted and downwardly tilted facets may visually cooperate with each other to simulate a gem.

5. An ornament having a gem simulating por-

tion integral with said ornament comprising a center portion consisting of a plurality of similarly inclined facets arranged in frusto-pyramidal formation and a border portion consisting

5 of a plurality of similarly inclined facets arranged in reverse frusto pyramidal formation around said center portion, with the facets of the center and border portions being similar to those of the gem to be simulated and having

10 highly reflective brilliant surfaces whereby the upwardly tilted and downwardly tilted facets may visually cooperate with each other to simulate a gem.

6. An ornament having a gem paved simulating surface comprising a plurality of multi-faceted frusto-pyramidal mounds projecting integrally upwardly from the surface thereof extending throughout a substantial predetermined area of the ornament surface so closely nested

20 as to have the faceted outer walls of each mound substantially abut the faceted outer walls of adjacent mounds, each mound having a concave crater comprising a multi-faceted indentation, with the facets of the mounds and indentations

25 being similar to those of the gems to be simulated and having highly reflective brilliant surfaces whereby the upwardly tilted and downwardly tilted facets may visually cooperate with each other to simulate the gems of a gem paved

30 ornamental surface.

7. An ornament having a gem paved simulating surface comprising a plurality of multi-faceted frusto-pyramidal mounds projecting integrally upwardly from the surface thereof ex-

35 tends throughout a substantial predetermined area of the ornament surface, each mound having a concave crater comprising a multi-faceted indentation, with the facets of the mounds and indentations

40 being similar to those of the gems to be simulated and having highly reflective brilliant surfaces whereby the upwardly tilted and downwardly tilted facets may visually cooperate with each other to simulate the gems of a gem paved ornamental surface.

45 8. An ornament having a gem simulating portion, comprising a multi-faceted frusto-pyramidal mound projecting integrally upwardly from the surface thereof having a concave crater comprising a multi-faceted indentation, with the

50 facets of the mound and indentation being similar to those of the gem to be simulated and having highly reflective brilliant surfaces whereby the upwardly tilted and downwardly tilted facets may visually cooperate with each other to simulate a gem.

EUGENE BAZNER.
